UNITED STATES PATENT OFFICE.

JAMES G. MACLAREN, OF MAMARONECK, NEW YORK.

CARRIER FOR PNEUMATIC-DISPATCH TUBES.

Application filed February 24, 1921. Serial No. 447,465.

To all whom it may concern:

Be it known that I, JAMES G. MACLAREN, a citizen of the United States, residing at Mamaroneck, in the county of Westchester 5 and State of New York, have invented certain new and useful Improvements in Carriers for Pneumatic-Dispatch Tubes, of which the following is a specification.

This invention relates to carriers for use 10 in pneumatic dispatch tube systems.

In modern department store pneumatic dispatch installations there is a rapidly increasing demand for carriers adapted to traverse the tube lines and to carry credit 15 or other memoranda slips so arranged and held that they can be classified and distributed to the proper authorizing clerks with the greatest possible speed and with a minimum degree of manipulation. The ordinary 20 carrier used in such installations comprises a short cylindrical casing designed primarily for use in making cash transactions and requiring the opening of the carriers and the removal of the credit slips for examination, and the replacement of the slips in 25 the carriers by the classifying clerks, before they were distributed to the authorizing clerks.

In the present invention a carrier is provided 30 for use in pneumatic dispatch tubes which is specially constructed to hold a folded credit slip in such manner that the information needed by the classifying clerk for distributing the slips to the proper authorizers is instantly available for examination without a preliminary opening or other manipulation of the carrier. Preferably the memorandum slip is held in place by a simple spring clip construction and can 35 be readily released for the use of the authorizing clerks and as readily reinserted in place in the carrier for re-dispatch to the customer's station.

In the drawing, in which a preferred embodiment of the invention is illustrated, 40

Figure 1 is a plan view of a carrier embodying the invention.

Figure 2 is a view in elevation of the carrier illustrated in Figure 1 and showing 45 the device in both its open and its closed positions.

Figure 3 is a view similar to Figure 2 and showing a slip held in place in the carrier.

55 Referring to the drawings for a more de-

tailed description of the device, two end members consisting of the felt buffers 1 are shown which are proportioned to the size and conformation of the tubes in which the carrier is to be used. The buffers 1 are attached in any suitable manner to the metal foundation plates 2 which are in turn attached to the opposite ends of the elongated U-shaped frame member 3 and which is adapted to serve as a support for a folded 60 memorandum slip 4 as indicated in Figure 65 3 of the drawing.

In order to hold a slip in place on the frame member 3 a clip member 5 is provided which is hinged in a yoke 6 carried by the 70 left-hand end of the frame member as shown. The clip member 5 can be swung to a raised inoperative position or to a lowered operative position as indicated in Figure 2 and is held in either position by the action of 75 the flat spring 7, attached to the frame member 3 and bearing on either of two flat faces of the block or bearing member 8 in which the clip member 5 is directly carried.

In operation a credit slip, so folded that 80 the name of the customer is uppermost, has its right hand end inserted in the slot 9, provided in the frame member 3, the left hand end of the slip bearing the initial letter of the customer's name being laid on 85 the frame member 3 in a position to underlie the open clip member 5 in the lowered or closed position thereof. The clip, which has been raised to permit of the placing of the slip in position, is now lowered into contact with the slip and, through the action of the spring 7 referred to, serves to clamp the slip securely against the upper surface of the frame member 3. Preferably a guard member 10 is provided which protects and 90 accommodates the ends of slips of various lengths.

It will be seen that with the construction described credit slips are securely held in condition to be conveyed through dispatch 100 tubes and in position to be quickly examined for classification according to the names or other information contained therein, and without any manipulation of the carrier or the slip holding means.

What I claim is:

1. A carrier for pneumatic dispatch tubes comprising terminal buffer members, an intermediate memorandum slip supporting member attached at its ends to said terminal 110

members, and means for clamping memorandum slips against said supporting member in position for ready inspection.

2. A carrier for pneumatic dispatch tubes comprising terminal buffer members, an elongated flat memorandum slip supporting member attached at its ends to said terminal members, and means for clamping memorandum slips against said supporting member in a display position.

3. A carrier for pneumatic dispatch tubes comprising terminal buffer members, an elongated flat memorandum slip supporting member attached at its ends to said terminal members, said supporting member being provided with a slot near one end for receiving and holding one end of a slip, and means mounted near the other end of the supporting member for clamping the slip against said supporting member.

4. A carrier for pneumatic dispatch tubes comprising terminal buffer members, an elongated flat memorandum slip supporting member attached at its opposite ends to said terminal members, said supporting member being provided with a slot near one end for receiving and holding one end of a slip, and a clip pivotally mounted near the other end of the supporting member and adapted to be swung into position to clamp the slip against the supporting member.

5. A carrier for pneumatic dispatch tubes comprising terminal buffer members, an elongated flat memorandum slip supporting member attached at its opposite ends to said terminal members, said supporting member being provided with a slot near one end for receiving and holding one end of a slip, a clip pivotally mounted near the other end of the supporting member and adapted to be swung into position to clamp the slip against the supporting member, and spring means for holding said clip either in its raised or its lowered clamping position.

6. A carrier for pneumatic dispatch tubes comprising terminal buffer members, an elongated flat memorandum slip supporting member attached at its opposite ends to said terminal members, said supporting member being provided with a slot near one end for receiving and holding one end of a slip, a skeleton clip member pivotally mounted near the other end of the supporting member and adapted to be swung into position to clamp the slip against the supporting member, the skeleton construction of the clip affording examination of the clamped slip, spring means for holding said clip in clamping position, and guard means for protecting the end of the slip projecting through said slot.

JAMES G. MACLAREN.
